US0D1072927S

(12) **United States Design Patent** (10) **Patent No.:** **US D1,072,927 S**
(45) **Date of Patent:** **** Apr. 29, 2025**

(54) **ELECTRONIC PIANO**

(71) Applicant: **YAMAHA CORPORATION**, Shizuoka (JP)

(72) Inventor: **Akie Hinokio**, Shizuoka (JP)

(73) Assignee: **YAMAHA CORPORATION**, Hamamatsu (JP)

(**) Term: **15 Years**

(21) Appl. No.: **29/917,901**

(22) Filed: **Nov. 22, 2023**

(30) **Foreign Application Priority Data**

Jun. 23, 2023 (JP) ..... 2023-012840 D

(51) **LOC (15) Cl.** **17-01**

(52) **U.S. Cl.**

USPC **D17/7**

(58) **Field of Classification Search**

USPC D17/1, 7, 9, 16, 18; D21/405, 409
CPC G10C 1/00; G10C 1/02; G10C 3/12

See application file for complete search history.

(57) **CLAIM**

The ornamental design for an electronic piano, as shown and described.

DESCRIPTION

FIG. 1 is a perspective view of an electronic piano showing my new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines shown in the figures depict portions of the electronic piano that form no part of the claimed design.

The dot-dash broken lines illustrate the boundary of the claimed design and form no part thereof.

1 Claim, 7 Drawing Sheets
